UNITED STATES PATENT OFFICE.

HAROLD C. EDDY, OF LOS ANGELES, CALIFORNIA, ASSIGNOR TO PETROLEUM RECTIFYING COMPANY OF CALIFORNIA, OF SAN FRANCISCO, CALIFORNIA, A CORPORATION OF CALIFORNIA.

ROTATING ELECTRODE CLOSED TREATER FOR PETROLEUM EMULSIONS.

Application filed February 28, 1921. Serial No. 448,550.

To all whom it may concern:

Be it known that I, HAROLD C. EDDY, a citizen of the United States, residing at Los Angeles, county of Los Angeles, and State 5 of California, have invented a new and useful Rotating Electrode Closed Treater for Petroleum Emulsions, of which the following is a specification.

My invention relates to devices used for 10 separating water from petroleum or other emulsions.

It is a well known fact that petroleum emulsions when subjected to the action of an electric field tend to break up, the water particles agglomerating to form large masses which settle out readily by the action of gravity.

It is also a well known fact that in many oils the dehydrating action is facilitated by 20 a movement of one of the electrodes or by an agitation of the material being treated.

It is a further well known fact that where electrodes upon which high electrical potentials are immersed in oil that there is considerable danger of electric discharges taking place over the surface of the oil with the result that in the ordinary open type of dehydrator fires are of frequent occurrence.

It is an object of my invention to provide 30 a dehydrator which is especially adapted for use on petroleum emulsions and in which an agitation of the fluid is possible and in which one of the two electrodes is rotated.

A further object of my invention is to 35 provide a dehydrator in which the fluid being treated is excluded from direct contact with the air, thus eliminating the danger of fire and conserving the lighter oil vapors.

A further object of my invention is to provide means in such a treater for cutting off the current whenever air is admitted to the interior thereof.

Further objects and advantages will be made evident hereinafter.

Referring to the drawing which is for 45 illustrative purposes only,

Fig. 1 is a view of a treater embodying my invention, this treater being shown partly in section and the electrical connections thereto being shown diagrammatically.

Fig. 2 is a section on a plane represented by the line 2—2 of Fig. 1.

Fig. 3 is a diagram showing a typical installation.

In the form of the invention illustrated in these drawings, 11 is a cylindrical tank which forms the grounded electrode and which has a tight bottom 12 and having a flared upper portion 13. Inside the flared portion 13 is a lip 14 to which a cover 15 is secured. Secured in the cover 15 is an insulator 16 having a central bore which may be lined with Babbitt metal 17. Secured by means of brackets 18 in the flared top 13 are insulators 19 having caps 20 on which a spider 21 is carried. This spider 21 has a sleeve 22 which projects inside the insulator 19. Rotating inside the sleeve 22 and in the Babbitt metal 17 is a rod 30 which is supported by means of an insulator 31 from a rod 32 which is rotated by any suitable mechanism, not shown. Secured on the rod 30 are discs 35. The rod 30 and discs 35 form the live electrode.

An outlet pipe 40 controlled by a valve 41 is secured in the bottom of the treater and an inlet pipe 42 is connected into the treater near the top thereof. A pipe 45 is connected into the cover 15, and is connected with a pipe 46 which connects to a small open top vessel 47 in which a float 48 is placed. This float is connected by a link 49 with one end of a lever 50 which is supported on a bracket 51 from a tank 47. Carried by the lever 50 but insulated therefrom is a brush 55 which connects contacts 56 and 57 when the float is in its upper position. Electric current of low potential is supplied through wires 60 and 61, a volt meter 62 being connected across these wires and an ammeter 63 being connected in the wire 61. A current limiting impedance 64 may be connected in the wire 60 and a second volt 65 may be connected between the wires 60 and 61 beyond the impedance 64. The wire 60 90 is connected into the primary 66 of a transformer 67. The wire 61 is connected to the contact 56 and the contact 57 is connected to the other side of the primary 66. The secondary 68 of the transformer 67 is connected

at a point 69 with the tank 11, the other side of the secondary 68 being connected to a wire 70 passing through an insulated bushing 71 and connected with the spider 21 and 5 thus with the rod 30 and the plates 35.

In practice I prefer to install the apparatus shown in Fig. 3 in which 100 is the treater illustrated in Figs. 1 and 2 and 101 is a trap tank connected at its bottom with 10 the treater 100 by the pipe 40 and having a water outlet pipe 102 controlled by a valve 103 and a clean oil outlet pipe 104. The vessel 47 is raised above the top of the tank 11 to the level of the pipe 104.

15 The method of operation is as follows:

The tank 11 being empty, the float 48 is in its lower position and the circuit to the primary 66 of the transformer 67 is interrupted at the contacts 56 and 57. Emulsion 20 is introduced through the pipe 43 filling the tank 11 and filling the trap tank 101. As soon as the level of the liquid in the trap tank 101 reaches the level of the pipe 104, oil passes upwardly through the pipe 45 25 into the tank 47 lifting the float 48. Since the pipe 45 is connected into the extreme top of the chamber formed by the treater 11 in the cover 15, any air or gas which may have been in the treater passes off through the 30 pipe 45 before this pipe fills with oil. It is, therefore, a certainty that as soon as the float 48 lifts, that the space inside the tank 11 below the cover 15 is entirely filled with oil. The lifting of the float 48 completes 35 the primary circuit through the contacts 56 and 57 and this circuit may be established at any time by energizing the wires 60 and 61. As soon as these wires are energized, the low potential in the primary 66 of the 40 transformer 67 induces a high potential of say 11,000 volts in the secondary 68, this high potential being impressed between the moving electrode formed by the rod 30 and the discs 35 and the grounded electrode or 45 tank 11. The discs 35 being rotated, the emulsion in the tank 11 is put in rotary motion, thus preventing short circuiting and insuring a rapid de-emulsification of the oil. Any gas or steam which may be formed in 50 the treater passes off through the pipe 45 which acts as a vent. As soon as the body of oil in the treater 11 is thoroughly de-emulsified which can ordinarily be determined by a man skilled in the art by the 55 reading of the ammeter 63 and the volt meter 65, the oil is started flowing at a regular rate through the pipe 42, this oil being introduced into the electric field between the electrodes and the water particles there- 60 in being agglomerated in this field so that they will readily settle out in the trap tank 101. The oil and water are delivered into the trap tank 101 in which a washing or separation takes place in accordance with 65 standard practice. The water settling in

the bottom of the trap tank 101 is drawn off through the pipe 102 and the cleaned oil is delivered through the pipe 104.

There are in operation in the United States many dehydrators having rotating electrodes operating in open tanks. These dehydrators are objectionable in that the oil is exposed to the air and often becomes ignited through flash overs on the surface of the oil or from other purposes. By entirely closing my treater, I am able to eliminate all fire risks. Closed treaters have, however, been used by others but these treaters are objectionable in that they are so constructed that they may at times be 70 partially filled with air in which case an explosion results in the event of a discharge in this confined space.

By equipping my treater with the float 48 and its connected parts, I am able to prevent both fires and explosions as no potential is impressed upon the treater except when the treater is entirely full and there is a sufficient head on the treater to raise the oil through the pipes 45 and 46 and to 80 raise the float 48.

It will be noted that the float 48 and its connected parts act to shut off the flow of electric potential applied to the treater whenever the level of the oil in the treater falls to a dangerous point. It will further be noted, however, that in effect the treater is always held under a slight pressure due to the difference in head between the float level in the top 15 of the treater. It will further be evident that whenever this pressure is reduced by a reduction of this head, that the float falls and interrupts the circuit. In other words, any reduction in fluid pressure inside the treater interrupts the 90 electric field produced by the current.

I would call particular attention to the location of the insulation in this treater, the greater portion of the weight being carried 100 on the insulators 19 which are outside of the oil. The insulator 16 is located in the top of the treater and at the center of the treater. Due to the centrifugal action of the rotating mass, the water particles are thrown outwardly and due to gravitation, they are drawn downwardly. The insulator 16 is, therefore, at the dryest and cleanest portion of the treater and insulator troubles are greatly reduced.

I claim as my invention:

1. A treater for petroleum emulsions comprising a tank; a cover closing the top of said tank; means for maintaining a fluid pressure on said tank; a vent pipe through which gases are permitted to escape from said tank; means for producing an electric field in said tank; and means for interrupting said field whenever the fluid pressure is reduced in said tank.

2. A treater for petroleum emulsions

- comprising a tank; a cover closing the top of said tank; means for maintaining a fluid pressure on said tank; a vent pipe through which gases are permitted to escape from said tank; a live electrode in said tank; means for rotating said live electrode; means for producing an electric field between said electrode and said tank; and means for interrupting said field whenever the fluid pressure is reduced in said tank. 35
- 5 5. A treater for petroleum emulsions comprising a tank; a cover closing the top of said tank; means for maintaining a fluid pressure on said tank; a vent pipe through which gases are permitted to escape from 40 said tank; a live electrode in said tank; means for rotating said live electrode; means for producing an electric field between said electrode and said tank; a vessel connected with said vent pipe and situated above the level of said cover; a liquid actuated float in said vessel; and means by which said float interrupts said electric field whenever the level of liquid falls in said vessel. 45
- 10 3. A treater for petroleum emulsions comprising a tank; a cover closing the top of said tank; means for maintaining a fluid pressure on said tank; a vent pipe through which gases are permitted to escape from said tank; a live electrode in said tank; means for producing an electric field between said electrode and said tank; a vessel 50 connected with said vent pipe and situated above the level of said cover; a liquid actuated float in said vessel; and means by which said float interrupts said electric field whenever the level of liquid falls in said vessel.
- 15 20 25 4. A treater for petroleum emulsions comprising a tank; a cover closing the top of said tank; means for maintaining a fluid

In testimony whereof, I have hereunto set my hand at Los Angeles, California, this 19th day of February, 1921.

HAROLD C. EDDY.
